UNITED STATES PATENT OFFICE.

ZOE B. SAY, OF NICKLEVILLE, PENNSYLVANIA.

INDEX.

SPECIFICATION forming part of Letters Patent No. 679,513, dated July 30, 1901.

Application filed March 21, 1901. Serial No. 52,163. (No model.)

To all whom it may concern:

Be it known that I, ZOE B. SAY, a citizen of the United States, residing at Nickleville, in the county of Venango and State of Pennsylvania, have invented certain new and useful Improvements in Indexes; and I do declare the following to be a full, clear, and exact description of the invention, such as will enable others skilled in the art to which it applies to make and use the same, reference being had to the accompanying drawing, and to the letters of reference marked thereon, which forms a part of this specification.

This invention relates to a novel index, designed primarily to simplify indexes kept by such establishments as require the opening of multitudinous accounts, and consequently the keeping of correspondingly-enlarged indexes.

The invention contemplates the dividing of a sheet into two sections adapted to receive separate series of entries and each section in turn divided into columns for the surname and Christian name of those with whom the account is opened. These columns are subdivided into various sections to accommodate the various letters of the alphabet, as will hereinafter more clearly and fully appear.

The invention further embraces the idea of providing to the left of the surname-column a series of consecutively-arranged numbers for indicating the letter box or file in which may be found the correspondence of the particular parties opposite whose names the numbers appear.

The invention still further relates to the provision of a general index to the right of each sheet, which will readily indicate just what portion of the index may be found before the sheet is examined and just what portion will be found thereafter and on what page. The details in the arrangement of the sheet will be apparent from the accompanying drawing, forming part hereof, when taken in connection with the detailed description hereinafter and the appended claim.

While in the drawing an embodiment of the invention is delineated for the sake of clearness in understanding the same, it is not intended to be limited to such specific construction and arrangement, inasmuch as slight alterations and changes in the less essential features may be made without in the least departing from the spirit of the invention.

In said drawing the view is a plan of a double-index sheet in its preferable arrangement, and referring more specifically to the same, A designates the marginal line of the index-sheet, adapted when used in book form to be folded on the line a. This sheet is divided by a vertical line B into the sections C C'. The section C' in operation is a continuation of the section C. Each section is divided near its left-hand edge into a vertical column D, designated the "Number" column, in which are consecutively-arranged numbers d, one for each line of the index, those on the sheet being from "12,675" to "12,678." Adjacent each number-column D are the relatively wider columns E E', designated, respectively, the "Surname" and the "Christian-name" columns, and these columns are subdivided as follows: The surname-column has provision for each letter of the alphabet corresponding to the initial letter of the name to be entered—"R," for instance—and the column has the transverse spaces e, dividing the same into relatively short sections in which the initial letter appears, together with each letter of the alphabet corresponding to the second letter of the surname, "RA," "RB," "RC," &c., "RA" only being shown in the drawing. The Christian-name columns are subdivided in the same manner as the surname-column, and in the dividing-spaces are arranged the different letters of the alphabet corresponding to the initial letter of the Christian name, "A" to "H" being shown in the drawing. The margins of the sheets below the index letters are cut away in an obvious manner. Adjacent the Christian-name columns are spaces F, entitled "Pages," in which may be indicated the page-number of the ledger upon which any particular account may be found. Next to these spaces are relatively wider spaces entitled "Residence" and forming columns G, in which the address of the parties may be found.

In finding the name in the index just described use the first two letters of the surname in the left-hand or surname column and the first letter of the Christian name in the second or Christian-name column—as, for instance, "Albert Race," the index "RA A"

should be examined, or "Henry Ransom," when the section "RA H" should be examined. In case of firm names—viz., "Rawls & Bros.," "Raines & Co.," or "Raymond & David," use the first letter of the "Bros.," "Co.," and "David," the same as if they were Christian names. To find the name "Raymond & David" upon the index at letter "R," run the thumb down the surname-
 10 index column to letters "RA" and also run down the Christian-name column to letter "D," where the name may be readily found, "David" appearing in the Christian-name column under said letter "D." Should the correspondence of a particular party be needed,
 15 its file-number may be seen in the number-column—as, for instance, "12,708" opposite "Raymond & David," and their address will be indicated in the residence-column as

To facilitate turning to various sections of an index-book provided with sheets of the character described, each sheet is provided adjacent its outer right-hand margin with 25 what I will term a "general index" H, the arrangement being as follows: To the extreme right in prominent type is the initial letter or letters of the surname section or sections appearing at the particular place to 30 which the book is opened, "R" appearing first on the sheet in the drawing, since this letter is the section being examined. To the left of these letters in less prominent type the second letter or letters of the surname
 35 appear "A" being the only one in this instance, since "RA" are the only letters to be found in the surname-columns. Still farther to the left are the initial letters of the Christian names appearing on the particular sheet, 40 "A" to "H" being shown on the sheet illustrated.

From the above description it will be apparent that an index is afforded in a relatively simple manner which possesses great advantages over any indexes of the prior art 45 in that it greatly reduces the labor incident to finding a particular account of a very large number.

Having thus described the invention, what is claimed as new, and desired to be secured 50 by Letters Patent, is—

An index-sheet comprising a series of relatively wide adjacent surname and Christian-name columns, characters corresponding to the initial and second letters of the surname 55 subdividing the surname-column into sections for the respective second letters, a second series of characters in horizontal alinement with the characters in the surname-column subdividing the Christian-name column 60 into a section for each letter of the alphabet, a relatively narrow appropriately-headed column adjacent the Christian-name column 65 subdividing the surname-column adapted to receive page-numbers, and a corresponding relatively narrow appropriately-headed column adjacent the surname-column 70 extending the full length of the sheet adapted to receive consecutively-arranged indicator characters, and a general index at the margin of the sheet comprising a surname initial letter or letters, a surname second letter or letters to the left thereof, and the Christian-name initial letter or letters adjacent the surname second letter or letters, the sheet being 75 cut away directly beneath the lowermost letter of each denomination, substantially as described.

In testimony whereof I affix my signature in presence of two witnesses.
